UNITED STATES PATENT OFFICE

CHARLES METZ, OF YOUNGSTOWN, OHIO

TOY HOOP ROLLER

Application filed December 4, 1930. Serial No. 500,027.

This invention relates to toys and more particularly to a hoop and means by which a hoop may be very easily retained in an upright position and rolled along a pavement or walk.

The principal object of this invention is to provide a guide and supporting means for a hoop which may be manufactured at low cost and allow for a handle member to 10 pivot upon a slide member which functions with the hoop.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within 20 the scope of what is claimed, without departing from the spirit of the invention.

The invention is illustrated in the accompanying drawing, wherein:—

Figure 1 is a perspective view of the device attached to a hoop.

Figure 2 is a cross section taken on line 2—2 of Figure 1.

Figure 3 is a detail view of Figure 1.

The parts used to propel a hoop 1 constitute the subject matter of this invention. It is understood that the hoop 1 may be of any convenient construction and also of any size desired. In order that the hoop 1 may be propelled in an upright position 35 there is provided a slideable support member

2 provided with loop ends 3 which function in a slideable manner with the hoop 1.

By referring to Figure 3 it will be seen that the slideable support member 2 is provided with a central loop portion 4 having a neck portion 5 for the purpose of supporting a handle 6 in a rotatable manner in relation to the neck portion 5. It will be seen that the handle 6 is provided with a 45 looped end 7 in order that the slideable support member 2 may be kept in a semi-vertical position in order to hold the hoop 1 in a vertical position for rolling.

While the handle 6 may be made of any 50 desirable material I prefer to use a twisted

wire consisting of two strands in order to give the same sufficient strength and durability to hold the hoop 1 and connecting parts in a vertical position.

By referring to Figures 1 and 3 it will be seen that a lower end 8 of the handle 6 is provided with a loop 9 which functions with the neck portion 5 in a rotatable manner in order that the handle may take any desired angle in relation to the slideable support 60 member 2.

What I claim is:—

1. In a device of the class described, the combination of a hoop with a slideable support member, looped ends formed on said slideable support member and encircling said hoop, a central loop portion, a neck portion formed on said central loop portion, a handle, a looped end on said handle encircling said neck portion so that said looped end may rotate on said neck portion, substantially as described.

2. The combination with a hoop of a slideable support member formed on one piece, loops formed on said slideable support member and encircling said hoop, a neck portion formed on said slideable support member, a handle, a central loop portion formed on outer end of said neck portion for the purpose of holding said handle in a rotatable manner upon said neck, a lower looped end formed on said handle and encircling said neck portion.

In testimony whereof I affix my signature.

CHARLES METZ.
